Primary Examiner — Nathan M Johnston

(74) Attorney, Agent, or Firm — Daniel M. Cohn;
Howard M. Cohn(57) **CLAIM**

The ornamental design for a storage rack as shown and described.

DESCRIPTION

FIG. 1 is a perspective view of a storage rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view of a storage rack as shown. The broken lines show portions of the storage rack that form no part of the claimed design.
